(No Model.)

A. L. REESE.

WHEAT DRILL.

No. 274,380.

Patented Mar. 20, 1883.

UNITED STATES PATENT OFFICE.

ABRAM L. REESE, OF CHASE, KANSAS.

WHEAT-DRILL.

SPECIFICATION forming part of Letters Patent No. 274,380, dated March 20, 1883.

Application filed May 10, 1882. (No model.)

To all whom it may concern:

Be it known that I, ABRAM L. REESE, of Chase, in the county of Rice and State of Kansas, have invented certain new and useful 5 Improvements in Wheat-Drills, of which the following is a full, clear, and exact description.

This invention relates to certain improvements in my improved wheat-drill for which 10 Letters Patent No. 256,049 were granted to me April 4, 1882.

Reference is to be had to the accompanying drawings, forming part of this specification, in which similar letters of reference indicate corresponding parts in all the figures.

Figure 1 is a plan view of my improved wheat-drill as it appears when fitted for running between rows of corn. Fig. 2 is a sectional elevation of the same, taken on the line $\alpha\alpha$ of Fig. 1. Fig. 3 is a side elevation; and Fig. 4 is a detailed sectional elevation, showing the rear end of the perforated block for adjusting and throwing out of action (by means of a rod entering the perforations of the block) two of the plow-points and colters.

AA represent the corresponding main frames of the drill, which are supported upon the axles BB of the wheels CC, which wheels are placed upon the axles so as to come about in 30 the center of the said frames. The adjacent ends of the axles BB are by preference upwardly bent to form the vertical portions aa, as shown in Fig. 1; and these vertical portions of the axles are correspondingly perforated 35 for the passage through them of suitable bolts for bolting the axles together when the drill is to be used on ordinary ground, or for attaching thereto the elevated or arch connection D when the drill is to be run between rows of 40 corn or other grain. This elevated or arch connection D is by preference composed of the two angle-bars, dd, which are adapted to be bolted at their lower ends by the bolts bb to the vertical portions aa of the axles, and to be secured together at their upper horizontal 45 ends by the bolts cc, as clearly shown in the drawings, and the upper horizontal portions of the said angle-bars are correspondingly perforated with the holes c, c', adapting the same 50 to hold the main parts of the drill nearer to or farther away from each other, as circumstances may require.

To the outer corners of the frames AA are secured the outwardly-projecting plates or castings ff, to which are attached the two colter-bars E E' and the two plow-point bars G G' in such manner that these bars are carried the proper distance outside of the frames AA, and so that they are adapted to have lateral movement to and from the frames, and also vertical movement, for the purposes hereinafter mentioned. The colter-bars E' and plow-point bars G' are by preference outwardly curved, as shown in Figs. 1 and 2, or they may be made straight, if desired.

H and H' H' represent the main colter-bars of the drill, six in number, three attached to each main frame AA, as clearly shown in Figs. 1 and 2; and J and J' J' represent the main plow-point bars of the drill. All of these colter-bars and plow-point bars are hinged to the under side of the frames AA in the manner shown and described in my above-mentioned patent, or in any other suitable manner, the bars H and J being arranged outside of the 75 wheels C, and bars H' and J' being arranged in the frames between the said wheels, as shown. The colter-bars are all downwardly bent, as shown in Fig. 3, and the plow-point bars are arranged under the horizontal portions thereof and reach past the colters j of the colter-bars, so as to carry the plow-points g immediately in rear of the colters, in the same manner as shown and described in my 80 said patent.

Extending rearward from the bends in the colter-bars E E' are the arms ee', and extending from the colter-bars H H' H' are the arms hh', which are precisely similar to the arms ee'. The arms ee' have attached to them the 90 cross-pieces FF, which tie the two colter-bars E and E' together and hold them at all times the proper distance apart, and the arms hh' have the cross-pieces KK attached to them, which tie the colter-bars H H' H' together and hold them at all times the proper distance apart. These cross-bars F and K serve also as means for simultaneously elevating the said 95 respective sets of colter-bars E E' and H H', and also the plow-point bars G G' and J J', by reason of their attachment to the colter-bars, as will be readily understood.

For elevating the cross-pieces KK, I provide the main frames AA with the rock-shafts

L L, formed with the arms v v, to which the cross-pieces are attached by suitable connections, and provide the rock-shafts with the hand-levers M M, for rocking the shaft for raising and lowering the said cross-pieces.

For elevating the cross-pieces F F, I pivot to the outside of the frames A A the rearwardly-extending levers N N, which pass through the staples l l, secured to the upper side of the cross-piece F, as shown in Figs. 1 and 3. These levers N N are adapted to have lateral movement as well as vertical, so that the colter-bars E E' and plow-point bars G G' may be carried by these levers to and from the frames A A to suit the drill to different widths of rows. In order to hold these bars at any desired vertical or outward position away from the frames, I secure to the outside side pieces of the frames A A the triangular blocks O O, which have the series of holes o o formed in them, as shown in Fig. 4, into which holes one end of the rods P P, which are attached to the levers N, are adapted to be placed, as shown in Fig. 3, a sufficient distance to serve as support for the said colter and plow-point bars, cross-piece F, and lever N.

Q represent the inside and R R the outside seed-boxes. These seed-boxes may be attached to the main frames A A in any suitable manner. The bottom s of the outside boxes, R, are of cast-iron and reach over the side colter-bars, E E', and plow-point bars G G', as shown in Figs. 1 and 2, and are formed with suitable discharge-orifices, i and i' i', through which the grain may be supplied from these boxes to the gutters formed by the colters and plow-points attached to these last-mentioned bars, and also to the gutters formed by the colter and plow-points on the bars H and J. The grain is conveyed from the discharge-orifices in the seed-boxes to the ground through the tubes k k, and suitable seed-dropping wheels will be used for dropping the grain from the seed-boxes into the tubes k k, which will, by preference, be of the same form and construction, and which will be operated from the wheels C C in the same manner as shown and described in my said Letters Patent. The discharge openings or orifices i' i' in the bottom s of the outside seed-boxes, R R, are fitted with the cut-off plates q q, by which the flow of grain through them may be stopped when it is desired to throw the side colter-bars, E E', and plow-point bars G G' out of action.

In use, when the drill is to be run upon ordinary ground, it will be understood that the elevated or arch connection D will be unbolted from the upward extensions a a, and the axles B B will be brought together, and the parts a a of the axles bolted firmly together.

When the drill is to be used for drilling between rows of corn the elevated or arch connection D will be replaced, in which condition the main parts of the drill are adapted to straddle a row of corn and drill the grain in the spaces between the rows, as will be clearly understood.

In case the spaces between two of the rows of corn are too narrow for the drill to operate without tearing up the corn, the cut-off plates q q may be moved to shut off the flow of grain to the gutters formed by the colters and plow-points upon the bars E E' and G G', and these bars may then be elevated and thus thrown out of action; or the said bars G G' and E E' may be carried nearer to the main frame to avoid injury to the corn and the whole left in action; or, in case the space between the rows is wider than usual, the said bars G G' and E E' may be carried by the levers N N farther away from the frames A A to suit the spaces.

Having thus fully described my invention, I claim as new and desire to secure by Letters Patent—

1. The combination, with axles B B, arranged about midway of the two main frames A A and bent up to form parts a a, of the two angle-bars d d, adapted to be bolted to one another and to said axle parts a, as shown and described.

2. In combination with the outer corners of frames A A, the projecting plates f f, carrying colter and plow-point bars, whereby said bars are carried outside the frame and allowed a vertical and lateral movement, for the purpose specified.

3. In a drill, the plates or castings f f, in combination with the side colter-bars, E E', and plow-point bars G G', substantially as described.

4. The blocks O, formed with the series of perforations o o, in combination with the rods P, levers N, cross-piece F, colter-bars E E', and plow-point bars G G', as set forth.

ABRAM L. REESE.
